UNITED STATES PATENT OFFICE.

WILLARD F. OLIVER, OF LYNN, ASSIGNOR TO BOSTON SHOE STUD AND
BUTTON COMPANY, OF BOSTON, MASSACHUSETTS.

IMPROVED SHOE-LACING.

Specification forming part of Letters Patent No. 82,022, dated September 8, 1868.

To all whom it may concern:

Be it known that I, WILLARD F. OLIVER, of Lynn, in the county of Essex and State of Massachusetts, have invented certain new and useful Improvements in Shoe-Lacings; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to shoe-lacings; and consists in providing the sides of the slit of a shoe with hooks or bearings so made and arranged that a lacing-cord may be conveniently slipped or looped over them for the purpose of drawing the sides of the slit together without the use of eyelets, and in providing the upper hood with a convenient device for holding the lacing-cord in place when the sides are thus drawn together.

In the drawings, Figure 1 is a perspective view, and Fig. 2 is a view of a part detached.

My hooks or bearings may be attached to the sides of the slits in various ways. For convenience in constructing them, I take two strips of metal, one of them long enough to extend from one end to the other of the slit B in a shoe, C, and the other long enough to extend nearly the length of the slit B, leaving space enough at the upper end to allow a separate hook, D, provided with a device, a, for fastening the cord, as shown in Fig. 2. The front edges of these strips I provide with hooks or bearings A, and their rear edge opposite the hooks with small projections, and then I fasten these strips to the sides of slit B by rivets b passing through the projections, and so that the hooks or bearings A, on each side, may alternate between each other, as clearly shown in Fig. 1. Near the upper end of the side upon which the shorter strip is placed I attach the upper or last hook, D, and to its side pivot an elbow-catch, a, so arranged that its lower arm, C, may bear against the lacing-cord E, when

passed through the hook to hold it in place, as clearly shown in Fig. 2.

One end of the lacing-cord E, I attach to the shoe C near the lower end of the slit B, and the other end of the cord may be attached to the upper part of the slit B, or to the hook D, as shown in Fig. 1.

After the shoe is placed upon the foot, all that is necessary to fasten it is, slip the cord E over the hooks or bearings A and the hook D, then draw it tight and fasten it with the catch a, or in any other desirable manner.

These hooks A may be made separately, instead of forming a part of a metal strip, as the hook D is, and then attached, my object being mainly to provide the slit B with alternating hooks or bearings, for conveniently fastening the shoe with a lacing-cord.

In the drawings I have shown my hooks or bearings A attached to a shoe to be laced up at the side. When the lacing is at the side, I prefer to have these hooks connected with metal strips, for the reason that these strips keep the sides of the slit straight and prevent them from wrinkling, or the top of the shoe from working down.

When the slit is in the front of the shoe, it is obvious that the metal strips, with the bearings A attached, cannot be used with the same utility and convenience, and I then attach the hooks or bearings A separately to the sides of slit, using a lacing-cord in the same manner as when the slit is at the side of the shoe, my object being the same—that is, to provide the slit with hooks or bearings over which the lacing-cord can be readily placed or looped, for convenience in fastening the shoe.

It is obvious that these hooks or bearings A may be arranged for the use of one or two cords, as desired. When two cords are used, the bearings should be placed opposite to each other, for convenience in lacing. By this means I provide a shoe with fastenings which do away with the use of holes or eyelets entirely, and, of course, avoids the delay and trouble of inserting the lacing through a series of holes, which trouble is frequently greatly increased by the loss of the metal point on the ends of the strings, and by the

strings, in such case, becoming unraveled, so that they cannot be readily put through the holes.

By my method of lacing, these metal points on the strings are rendered entirely unnecessary, thus cheapening the manufacture of the strings also, and both ends, being made fast, are not exposed for unraveling.

Having thus described my invention, what I claim is—

1. A shoe provided with a series of hooks,

or their equivalents, for receiving and holding the string, when arranged substantially as set forth.

2. The catch or clamp *a*, with its arm *c* pivoted to the hook *D*, and arranged for holding the string, substantially as described.

WILLARD F. OLIVER.
